UNITED STATES PATENT OFFICE.

GEORGE E. GOODING, OF BOSTON, MASSACHUSETTS, ASSIGNOR TO JOHN T. ROBINSON COMPANY, OF BOSTON, MASSACHUSETTS, A CORPORATION OF MASSACHUSETTS.

MECHANISM FOR ADJUSTING CREEPING ROLLS.

Application filed May 28, 1927. Serial No. 195,110.

This invention relates to machines for operating upon sheet material, and especially to machines for creasing and scoring cardboard and similar stock in the preparation of the blanks which are subsequently folded to make paper boxes. The invention has for its general object to facilitate the setting and adjustment of the creasing and scoring devices in accordance with the requirements of the particular work to be done. It is a further object of the invention to provide a gauge whereby the central planes of the effective creasing portions of cooperating adjustable creasing members may be aligned accurately and readily without special skill or experience.

The foregoing and other objects of the invention together with means whereby the latter may be carried into effect will be best understood from the following description of a preferred embodiment thereof illustrated in the accompanying drawings. It will be understood, however, that the particular construction described and shown has been chosen for purposes of exemplification merely and that the invention as defined by the claims hereunto appended may be otherwise embodied without departure from the spirit and scope thereof.

30 In the drawings:

Fig. 1 is an end elevation partially broken away of a scoring and creasing machine embodying the invention and having applied thereto a gauge for setting the creasing devices, the gauge in this instance being applied for setting the upper creasing members.

Fig. 2 is a plan view thereof.

Fig. 3 is a front elevation of a portion of the machine showing the gauge applied thereto for setting the lower creasing members.

Fig. 4 is a section taken on line 4—4, Fig. 3.

Fig. 5 is a perspective view of the gauge.

Fig. 6 is an enlarged front elevation of one of the upper creasing members showing the application of the gauge for setting said member.

Fig. 7 is a similar view showing the application of the gauge for setting a lower creasing member.

50 Fig. 8 is an enlarged detail view of a portion of the stock showing the impression formed by the scoring and creasing devices.

Usually scoring and creasing machines of the type to which the present invention relates comprise a plurality of units through

which the stock is passed to crease and score the same along the desired parallel lines. For the purpose of illustration, only one unit is indicated in the machine shown in the drawings. This machine comprises a bar 23 mounted in fixed position in the machine and a shaft 24 disposed parallel and adjacent to the bar 23. Conveniently, and as herein shown, the frame of the creasing and scoring mechanism may include a pair of parallel side uprights 25 between which a suitable table (not shown) as well as the bar 23 are supported, said uprights carrying suitable bearings in which the shaft 24 is journalled. Suitable means are also provided for 60 rotating the shaft 24. As shown the shaft 24 is provided with a driving pulley 31 to which power from any suitable source may be applied through a belt (not shown).

Separately, detachably, and adjustably 75 mounted on the bar 23 are creasing and scoring devices corresponding in number and arrangement to the scored and creased lines of the blank. Preferably, as shown, the creasing devices 32 and scoring devices 33 80 comprise disks or wheels rotatably mounted in carriers 34 adjustable as by adjusting screws 35 in holders 36 detachably secured as by set screws 37 to the bar 23. It will be seen that the holders 36 with their creasing and scoring devices can be applied at will to the bar 23 or removed therefrom or adjusted therealong transversely of the machine in accordance with the requirements of the work.

The creasing devices 32 have peripheral 90 surfaces shaped to cooperate with complementary surfaces on the shaft 24 to crease or score the stock S as indicated at c and s respectively in Fig. 8. To this end and as most clearly shown in Fig. 7 the creasing wheel or disk 32 is formed with a peripheral groove which receives a rib 38 on the shaft 24. Each rib 38 is formed on a ring or collar 39 adjustably secured to said shaft as by a clamping screw 40 (Fig. 4) having a head engaging an undercut groove 40^a in the shaft, whereby

95 said ring or collar may be adjusted along said shaft in accordance with the adjustment of the complementary creasing wheel 32 on the bar 23. Preferably the ring or collar 100 is split to facilitate its application to and removal from the shaft, and the two sections are secured in assembled relation about the shaft by bolts or screws 41.

105 The bar 23, while occupying a fixed opera-

tive position in the machine, is preferably pivotally mounted therein to turn about a fixed transverse axis into operative or inoperative position. As shown, said bar is 5 formed with trunnions 43 suitably journalled in the uprights 25 and is provided with an operating handle 44, whereby it may be readily turned upon said trunnions into the operative position shown in Figs. 3, 4 and 7 10 or into the inverted or setting position shown in Fig. 1. The handle 44 cooperates with a fixed segment 45 carried by one of the side uprights 25 and is provided with a pivoted manually operated latch 46 cooperating with 15 openings 47 in said segment, whereby the bar may be locked in either position. When the bar is in operative position, the creasing and scoring devices thereon are brought into cooperative relationship with the complementary 20 surfaces on the shaft 24, and when said bar is turned into its inverted position, said creasing and scoring devices are brought into a position adjacent the top of the machine where they can be conveniently applied 25 to, removed from, or adjusted on the bar.

For the purpose of facilitating the setting of the creasing and scoring devices in their proper relative positions on the bar 23 and shaft 24, the collocating instrument most 30 clearly shown in Figs. 1 and 2 may be provided. As shown, said instrument comprises a bar 48 extending transversely across the machine and carried at its ends by slides 49 mounted for movement longitudinally of the 35 machine on guides or rods 50 carried by brackets 51 secured to the tops of the uprights 25. Secured as by set screws 52, to the bar 48 are straps 53 connected by hinges 54 to a suitable scale 55. It will be seen that the 40 instrument can be moved longitudinally of the machine into juxtaposition with the bar, the hinged mounting of the scale 55 facilitating this operation when the bar is turned into setting position, and said scale employed 45 for co-locating and setting of the several creasing and scoring devices on the bar 23.

In accordance with one feature of the invention the co-operating creasing members are provided with points equidistant from or 50 bearing some other definite relation to the central plane of the effective creasing portion thereof so that said central planes may be aligned accurately and readily without special skill or experience by a gauge. In the embodiment of the invention illustrated the 55 radial face 60 of the creasing disk or wheel 32 is spaced from the central plane of the effective creasing portion of said wheel a distance equal to or which bears a definite relation to the distance which the radial face 61 on the 60 collar 39 is spaced from the central plane of the effective creasing portion of the rib 38 on the collar 39.

A gauge G is provided which is adapted 65 to embrace or fit over the edge of one of the

cooperating creasing members. In the form illustrated, this gauge comprises two members having faces 62 and 63 spaced apart to fit over the creasing wheel or disk 32 and connected by a portion 64 having a part, such as a hair line impression 65, thereon located in a plane having a definite predetermined relation to one of the faces 62 and 63 when engaging a predetermined surface of the disk 32 so that this line will lie in the central plane 70 of the effective creasing portion of the disk. In order that the gauge may be placed upon the disk 32 and held securely thereon during the adjusting and setting operation, the gauge is provided with a threaded opening 66 to 75 receive a clamping screw 67. In order that the central plane of the effective creasing portion of the rib 38 on the collar 39 may be aligned with the central plane of the effective creasing portion of the disk 32, one of the 80 faces of the gauge is provided with a projection 68 having a face which is adapted to engage a predetermined point or surface upon the collar 39, herein shown as a radial face 61, when the gauge is fitted over the edge of the 85 disk 32 to bring the central planes of the effective creasing portions of the rib 38 and disk 32 into a common plane. 90

When it is desired to adjust or set the co-operating creasing members, the bar 23 is 95 turned to the inverted or inoperative position shown in Figs. 1 and 2. The scale 55 is then turned upon its hinge 54 into proximity with the creasing members. The gauge G is then 100 fitted over the edge of one of the creasing members upon the bar 23 with the hair line in the central plane of the effective creasing portion thereof. The creasing member is then adjusted to bring the hair line at a desired point upon the scale. Without changing 105 its relation to the adjusted creasing member, the gauge is then brought to a position within the path of adjustment of the creasing member cooperating with the adjusted creasing member and thereafter predetermined points 110 or surfaces of the gauge and cooperating creasing member are brought into engagement thereby aligning the central planes of the effective portions of the two creasing members. In this manner the various cooperating creasing members are adjusted upon 115 the machine relative to each other as desired.

What I claim is:

1. In a creasing machine, in combination, an adjustable creasing member, a scale, and a gauge positioned with a surface engaging a surface of the creasing member and having a part cooperating with said scale to locate the effective creasing portion of the creasing member with respect to said scale. 120
2. In a creasing machine, in combination, an adjustable creasing member, a scale, and a gauge positioned with a surface engaging a radial face of the creasing member and having a hair line cooperating with the scale to 125

locate the effective creasing portion of the former with respect to the latter.

3. In a creasing machine, in combination, an adjustable creasing member, a scale, a 5 gauge positioned for cooperation with said scale and having parallel faces one of which is adapted to engage a radial face of said creasing member, and a clamping member co-operating with the other face for securing the 10 gauge to the creasing member.

4. In a creasing machine with cooperating adjustable creasing rings and creasing wheels, a gauge engaging a predetermined surface of one of said creasing members and having a 15 projection adapted to engage a predetermined surface on the other of said members, said gauge being so constructed that the central planes of the effective creasing portions of said members are alined when said surfaces 20 of said members engage respectively said positioning surfaces of said gauge.

5. In a creasing machine with cooperating adjustable creasing rings and creasing wheels each having a surface equidistant from the 25 central plane of the effective creasing portion, a gauge for locating the relative positions of said rings and wheels and having a face adapted to engage said surfaces of said creasing ring and creasing wheel to bring said 30 central planes thereof into a common plane.

6. In a creasing machine with cooperating adjustable creasing rings and creasing wheels having a positioning surface, a gauge having a surface cooperating with said positioning

surface for locating the relative positions of 35 said rings and wheels and means for clamping said gauge on one of said members.

7. In a creasing machine with cooperating adjustable rings and wheels, a scale movably mounted thereon and adapted to be brought 40 into proximity with one of said creasing members, and a gauge adapted to fit over the edge of said member and having a hair line locating the central plane of the effective creasing portion thereof whereby the latter 45 may be brought to a desired point relative to said scale, said gauge having a projection adapted to be brought into engagement with a predetermined point on the other of said members without changing its position relative to said first member and thereby align 50 the central planes of the effective creasing portions of said members.

8. In a creasing machine with cooperating adjustable creasing rings and creasing wheels, 55 a scale, a gauge for locating the relative positions of said rings and wheels adapted to fit over the edge of one of said creasing members and having a hair line locating the central plane of the effective creasing portion thereof 60 relative to said scale, said gauge having a projection adapted to engage a predetermined point on the other of said members to bring into alignment the central planes of the effective creasing portions of said members. 65

In testimony whereof I affix my signature.

GEORGE E. GOODING.
